UNITED STATES PATENT OFFICE.

KARL JOSEF STRIGL, OF NEW YORK, N. Y.

ROUNDABOUT.

Application filed April 14, 1927. Serial No. 183,744.

This invention relates to new and useful improvements in round abouts, and may be constructed in miniature form for providing a toy or may be constructed in a larger form for providing a passenger carrying amusement apparatus for use in resort parks and the like.

In carrying out the present invention, there is provided an aeroplane simulating unit having a motor arranged within the body thereof for rotating the propeller, a supporting frame being provided for suspending the aeroplane, in such a manner as to enable the same to rotate therein, due to the rotation of the propeller.

In the preferred embodiment of the invention, a suitable electric motor is arranged within the body of the aeroplane and operatively associated with the propeller, means being provided for conducting current to the motor, while the same is travelling in a circular path, said means being of simple and efficiently operating construction.

In the drawings, wherein for the purpose of illustration is shown the preferred embodiment of my invention:

Figure 1 is a side elevation of my improved roundabout, the aeroplane unit being disposed in full line operating position, and in dotted line stationary position.

Figure 2 is a view in side elevation, of the aeroplane unit, partly broken away for disclosing the motor drive for the propeller and the means for conducting the electric current to the motor at all positions of the aeroplane within the supporting frame structure.

Figure 3 is an enlarged transverse section taken through the aeroplane, and through the current conducting unit.

Figure 4 is a horizontal section through the unit, taken substantially upon the line 4-4 of Figure 3, and

Figure 5 is a section through the supporting socket for the aeroplane suspending bar having a ball upon the upper end thereof for loose disposition within said socket.

Now having particular reference to the drawings, my novel invention consists of a suitable supporting structure preferably consisting of an elevated horizontal bar 5 and vertical supporting legs 6-6 at the ends thereof. Arranged upon the under side of the horizontal bar 5 of the frame, and at the center thereof, is a semi-spherical shaped

socket 7, formed at its bottom side with a circular opening 8. The invention further consists of an aeroplane simulating unit 9, having passenger seats 10-10 within the fuselage thereof and upon the forward end 60 of which is arranged a suitable propeller 11. Within the fuselage is an electric motor 12, the armature shaft 13 of which extends forwardly and is operatively connected to said propeller. Directly in front of the 65 motor 12 is a pair of spaced vertical standards 14-14 to which are pivoted the ends of an inverted V-shaped bracket 15, provided at its upper end with a pin 16, upon the end of which is a bearing plate 17. 70

Arranged upon the bracket 15 and through the center of which projects the pin 16 is a circular plate 18, provided upon its top side with a pair of spaced concentric conductor rings 19-19, that are electrically connected 75 to the motor 12 by the wires disclosed in Figure 3. Said pin 16 projects through the bottom wall of a circular cup 20, while arranged between the bottom wall of said cup and the plate 17 of the pin 16 are bearings 80 21. Threaded within the upper end of this cup 20 is a plug 22, through the center of which is rigidly arranged the lower end of a hollow suspension bar 23 and through which electric conducting wires 24-24 pass, 85 the lower ends thereof being attached to electrical brushes 25-25 arranged within arm carrying sleeves 26-26 upon the outer side of the cup 20, which brushes are preferably of the spring depressed character for 90 wiping engagement with the circular conductors 19-19.

The upper end of the suspension bar 23 is equipped with a ball shaped head 27, arranged within the frame carrying socket 7. 95 The wires 24-24 extend through an opening 28 in the upper end of this bar 23, after which they are extended to a suitable switch 29, located upon the frame and in circuit with a source of electric supply.

Obviously, when the motor 12 is under operation, the propeller 11 will be rotated, for causing the travel of the aeroplane 9 in a circular path as indicated by the arrows in Figure 1. Preferably, the aeroplane 9 is 105 equipped with the usual steering rudder 30, at its rear end, and operatively connected with a steering wheel 31 within the aeroplane body, that may be operated by a passenger within the aeroplane or that may be 110

set prior to the operation of the device, for regulating the path of movement of the aero-plane.

The form of the invention shown and described is for use in the carrying of passengers at an amusement park or the like, but it is to be understood that the roundabout may be constructed of miniature formation and the propeller 11 operated by a small electric or spring motor within the aeroplane so that the device may be employed by children on a table or other support. Furthermore the roundabout unit may be of a formation other than an aeroplane as shown. The suspension member may also be in the form of a chain, cable or the like.

Having thus described the invention, what I claim as new is:

1. In a roundabout of the character described, a supporting frame, a socket associated with an elevated unit of the frame, a roundabout unit, a suspension member, a head at one end of the member for universal movement within the frame socket, and a pivotal and rotary connection between the opposite end of the member and said roundabout unit, said pivotal connection consisting of a bracket pivoted to the roundabout unit, a pin upon the upper end of the bracket, a cup arranged over the upper end of the pin, a disc upon the inner end of the pin for engagement with the bottom wall of the cup, a plug within the upper end of the cup, and a connection between the plug and the adjacent end of said suspension member.
2. In a roundabout of the character described, a supporting frame, a socket associated with an elevated unit of the frame, a roundabout unit, a suspension member, a head at one end of the member for universal movement within the frame socket, and a

pivotal and rotary connection between the opposite end of the member and said roundabout unit, said pivotal connection consisting of a bracket pivoted to the roundabout unit, a pin upon the upper end of the bracket, a cup arranged over the upper end of the pin, a disc upon the inner end of the pin for engagement with the bottom wall of the cup, a plug within the upper end of the cup, and a connection between the plug and the adjacent end of said suspension member, said roundabout unit being in the form of an aeroplane, a propeller mounted for rotation upon the forward end of the plane, an electric motor within the plane and operatively connected with said propeller, a plate arranged upon the bracket pin beneath the cup, a pair of spaced concentric contact rings arranged upon the top face of the plate, a pair of electrical contact brushes associated with the cup for engagement with the contact ring, and having circuits with a source of electric supply, said contact ring being in circuit with the motor.

3. In combination, a suspension member, a roundabout, means for attaching the roundabout to the suspension member, comprising a pin extending upwardly from the roundabout, a cup having an opening in the bottom thereof through which said pin extends, a head on the upper end of the pin arranged within the cup, said cup being adapted for rotation about the pin, a plug removably secured in the upper open end of the cup, the lower end of the suspension member extending through the plug, and a head carried by the lower end of the suspension member for disposition within the cup against the underside of the plug.

In testimony whereof I affix my signature.
KARL JOSEF STRIGL.
